BODY FOR A HELICOPTER

Edward F. Katzenberger, Bridgeport, Conn., assignor to United Aircraft Corporation, East Hartford, Conn., a corporation of Delaware

Application May 28, 1949, Serial No. 2,928

Term of patent 7 years

(Cl. D71—1)

To all whom it may concern:

Be it known that I, Edward F. Katzenberger, a citizen of the United States, residing at 10 Washington Avenue, Bridgeport, in the county of Fairfield and State of Connecticut, have invented a new, original, and ornamental Design for Body for a Helicopter, of which the following is a specification, reference being had to the accompanying drawing, forming a part thereof.

Fig. 1 is a top plan view of a body for a helicopter, showing my new design.

Fig. 2 is an elevational view showing one side of the helicopter body.

Fig. 3 is an elevational view showing the other side of the body.

Fig. 4 is a front view of the body.

I claim:

The ornamental design for a body for a helicopter, as shown.

EDWARD F. KATZENBERGER.
